CASTRATION CLAMP

Noah E. Schoonover, Fort Rice, N. Dak., assignor
of forty-five per cent to Fred Westerman, Fort
Rice, N. Dak.

Application October 5, 1934, Serial No. 747,051

1 Claim. (Cl. 128—306)

This invention relates to a castration clamp, and has for its principal object the production of a simple and efficient clamp having a stationary jaw and a movable jaw which movable jaw is adapted to be forced into clamping engagement with the stationary jaw.

A further object of this invention is the production of a castration clamp which is so constructed as to effectively crush the cord or testicle sack in such a manner as to prevent the breaking of the skin or the drawing of blood.

A still further object of this invention is the provision of a simple and efficient means for tilting the adjustable jaw in such a manner as to prevent the sack or cord from moving outwardly from a position between the jaws while the movable jaw is being adjusted to a clamping position.

A still further object of this invention is the production of a simple and efficient mounting for the adjustable jaw of the clamp whereby the adjustable jaw will be tilted with respect to the stationary jaw to cause the outer ends of the jaws to converge while the adjustable jaw is being moved to a clamping position.

With these and other objects in view this invention consists in certain combinations and constructions which will appear throughout the following specification and claims.

In the drawing:—

Figure 1 is a side elevation of the clamp in a closed position;

Figure 2 is a front elevation of the clamp;

Figure 3 is a side elevation of the clamp in an open position, certain parts being broken away and shown in section; and

Figure 4 is a section taken on line 4—4 of Figure 1.

By referring to the drawing, it will be seen that 10 designates the stationary jaw which is carried by an elongated shank 11 constituting a handle. The stationary jaw 10 extends at substantially right angles to the shank 11 and is provided with a rounded lower face 12 to provide a smooth contacting face in order to avoid presentation of any sharp or cutting edges. The shank 11 carries a pair of guiding plates 13 which plates are securely held against the faces of the shank 11 by means of suitable rivets 14. Each plate 13 is provided near its lower end with a projecting arm 15 between the outer ends of which arms 15 is mounted an operating lever 16 by having its outer end 17 pivotally mounted upon the supporting pin or bolt 18. This bolt or pin 18 is carried by the outer ends of the arms 15. The outer end 17 of the operating lever 16 is offset

or extends at substantially right angles to the shank portion 19 of the lever 16 and this operating lever 16 is provided with a cam face 20 along its upper edge for the purpose hereinafter described. The shank portion 19 of the lever 16 carries a link 21 which link is adapted to engage the rack 22 carried by the shank 11 for the purpose of holding the lever 16 in a closed position such as is shown in Figure 1.

An adjustable jaw 23 having a shank portion 24 is slidably mounted between the plates 13 and the adjustable jaw 23 is provided with a rounded upper face 25 similar to the rounded lower face 12 of the jaw 10 to provide a smooth contacting clamping face thereby avoiding presentation of any sharp or roughened edges having contact with the flesh of the animal which is being operated upon. The shank portion 24 of the adjustable jaw 23 is provided with an arc-shaped longitudinally extending slot 26 through which slot 20 extends a guiding pin or bolt 27 carried by the plates 13. The arc-shaped slot 26 has its respective ends extending toward the rear or inner edge 28 of the shank portion 24, as shown in Figure 3. A second guiding slot 29 is formed in the shank 25 below the arc-shaped slot 26. This guiding slot 29 extends on an incline or at an angle to the longitudinal axis of the shank 24, the slot 29 being pitched from its lower end near the forward edge 30 of the shank 24 toward its top near 30 the inner edge 28 of the shank 24, as shown in Figure 3.

An anchoring pin 31 is carried by the plates 13 below the pin 27 and extends through the slot 29.

Secured to the shank 24 near its upper end by means of a suitable eye or other securing means 32 is a tension coil spring 33, the lower end of the spring 33 being secured to a yoke 34, the yoke 34 being anchored upon the bolt or pin 18 and 40 straddling the arms 15, as shown in the drawing.

The operation of the device is as follows:—

The cord or testicle sack is placed between the jaws 10 and 23, and by carefully considering Figure 3, it will be seen that the upper face 25 of the jaw 23 is slightly tilted to restrict the opening between the outer ends of the jaw 10 and jaw 23 when the jaws are in an open position. This will tend to prevent the cord or sack from slipping out of position between the jaws as the adjustable or movable jaw 23 is moved to a closed position. This tilting position of the jaw 25 is accomplished by the position of the pin 23 and the pin 27 within the respective slots 26 and 29. When these pins 55

are in the upper ends of the slots 26 and 29, the shank 24 will be inclined, as shown in Figure 3, but as the jaw 23 is moved toward the jaw 10 the pin 31 by sliding in the inclined slot 29 will cause the shank 24 to move toward the shank 11 and to a substantially parallel position and the arc-shaped slot 26 by riding over the pin 27 will also assist in moving the shank 24 to a parallel position with respect to the shank 11. The shank 24 is moved longitudinally or to a closed position with respect to the jaw 10 by swinging the lever 16 toward the shank 11 thereby causing the cam face 20 to engage the lower end of the shank 24 and push the shank 24 longitudinally between the plates 13 to a clamping or closed position, such as is shown in Figure 1. The lever 16 may be held in this clamped position through the medium of the link 21 engaging the rack 22. When it is desired to move the adjustable jaw 23 to an open position, the lever 16 may be swung to the position shown in Figure 3 and the coil spring 33 will immediately pull the shank 24 downwardly to an open position and away from the inner face of the shank 11, such as is shown in Figure 3, causing the shank 24 to assume an inclined position, the lower end of the shank 24 being at all times in frictional engagement with the cam face 20 through the medium of the coil spring 33.

It should be understood that certain detail changes in the mechanical construction, combination and arrangement of parts may be em-

ployed without departing from the spirit of the invention so long as such changes fall within the scope of the appended claim.

Having described the invention, what is claimed as new is:—

A clamp of the class described comprising a stationary jaw, a shank supporting the stationary jaw, plates carried by the stationary jaw and extending laterally thereof, a movable jaw having a shank slidably mounted between said plates, lever means engaging said movable jaw for moving said movable jaw in one direction longitudinally of the plates, spring means for automatically drawing the movable jaw to an open position when pressure is released from said lever means, a pin carried by said plates, an inclined guiding slot formed in said shank of said movable jaw, said slot being inclined toward the inner face of the shank from its bottom toward the top thereof whereby said shank of said adjustable jaw will be inclined outwardly at its bottom when said shank is in its lower position, and whereby said shank of said adjustable jaw will extend substantially parallel to the shank of the stationary jaw when the stationary jaw is in a closed position, a longitudinally extending arc-shaped slot formed in the shank of the adjustable jaw, and a pin carried by the plates extending through said arc-shaped slot.

NOAH E. SCHOONOVER.
